LAMP SOCKET

Joseph Wertzheiser, Bronx, N. Y., assignor to
 Leviton Manufacturing Company, Brooklyn,
 N. Y., a corporation of New York

Application April 6, 1937, Serial No. 135,206

7 Claims. (Cl. 173—348)

This invention relates to a lamp socket that is particularly useful in connection with lamp bulbs that have more than one filament, but it is not restricted to this type of lamp.

- 5 In carrying out this invention the parts are assembled in a compact manner so that they are securely held in place and a switch operating member is journaled so that it is steady and does not vibrate and the switch closing member does
 10 not cause flickering when the current is turned on and off.

The invention will be understood from the description in connection with the accompanying drawings, in which Fig. 1 is a side view of an 15 illustrative embodiment of the invention; Fig. 2 is a longitudinal section through the device on an enlarged scale; Fig. 3 is a similar section at right angles to Fig. 2; Fig. 4 is an end view of the device; Fig. 5 is a section along the line 5—5 of 20 Fig. 2; Fig. 6 is a section along the line 6—6 of Fig. 2; Fig. 7 is a section along the line 7—7 of Fig. 2; Fig. 8 is a side view of the switch closing mechanism; Figs. 9 and 10 are views similar to Fig. 2 showing parts in different positions; Figs. 25 11 and 12 are side views of a modification of the switch closing mechanism and Fig. 13 is a section along the line 13—13 of Fig. 11. Fig. 14 is an elevational view of the fiber plate 37.

In the drawings, reference character 1 indicates a base of insulating material, such as porcelain for example. A fiber disk 2 lies against the lower end of the base 1 and is attached thereto together with a cup shaped screw shell 3 which is for a lamp bulb indicated by the reference character 4. This lamp is shown with two filaments 5 and 6, one end of the filament 5 being connected to the screw shell 7 of the bulb, as indicated at 5' and one end of the other filament 6 is connected to this shell 7, as indicated at 40 6'. The lamp bulb is provided with a center contact 8 for one of the filaments and also with annular contact 9 for the other filament.

A cut out portion 10 is provided at the bottom and adjacent sides of the shell 3 in the usual 45 way. Screw bolts 11 and 12 (Fig. 3) are provided for attaching the shell 3 and disk 2 to the base 1. A terminal 13 is provided in a recess 14 in the base 1 into which recess the screw 11 extends. A binding screw 15 is provided on the terminal 13 for one side 15' of the circuit. A nut 16 is provided in another recess 17 in the base 1 for the screw 12. A U-shaped center contact 18 (Figs. 2, 8 and 10) is held in the base 2 by a rivet 19 at the center of the disk 2. An L-shaped off center contact 20 is attached to the

base 1 for the contact 9. It is held on the base 1 by the screw bolt 21. This screw bolt 21 also holds in place a spring contact 22 for the make and break switch, to be described, in a recess 23 opening out from the bottom of this base. A 5 nut 24 is provided for the screw bolt 21 in the recess 25 at the top of the base 1 and sealing material 26 is provided for this nut and the end of this bolt.

A U-shaped spring contact 27 is also held by 10 the rivet 19 in the recess 23 for the switch.

A screw bolt 28 is provided in the recess 23 in the base 1 and is screwed into the terminal 30 in the recess 31 for keeping this terminal in place. A binding screw 32 is provided on the terminal 15 31 for the other wire 32' of the circuit. A spring contact 34 for the switch is also held in place in the recess 23 by the screw 28. A fiber plate 37 (Figs. 2 and 3) is provided along one side of the recess 23 between the fiber disk 2 and the end 20 of the recess 23.

A recess 38 (Figs. 3 and 4) is provided in the end and side of the base 1, this recess opening into the recess 23. Lugs 39 (Figs. 3 and 4) integral with the base 1 are provided along opposite walls of the recess 38 and an U-shaped support 40 for the switch shaft to be described are provided along opposite walls of the recess 38. A screw 41 passes through a hole 42 in the long side of the support 40 and screws into a threaded 30 hole 43 in the short side of this support. A slot 44 is provided at the end of the long side of the support 40 for receiving the switch operating shaft 46, thus providing a bearing therethrough. This shaft is provided at the end thereof with an 35 operating knob or button 47 of insulating material. An annular groove 48 is provided in the shaft 46 for the slotted end 44 of the support 40. The intermediate portion of the shaft 46 is reduced in diameter as indicated at 49 and the inner end thereof is further reduced, as indicated at 51, and is journaled in a hole 50 in the fiber plate 37. A coil spring 52 is provided on the shaft 46, one end 53 of this spring extending parallel to the shaft in a slot 54 of its larger part 45 and the other end 55 of this spring extends axially of the shaft into a hole 56 in a revolvable switch member or commutator 57.

The commutator 57 is made of insulating material and is provided with a hole 58 therethrough 50 for the end 51 of the shaft 46. It is also provided with an enlarged recess 59 for the end of the intermediate portion 50 of the shaft 46. This commutator 57 is rotatably mounted on the shaft 46 and is connected to and turned by said shaft 55

through the spring 52. The commutator does not move immediately upon the turning of the shaft, but moves only after sufficient tension to overcome the forces holding the switch member 5 has been built up in the spring 52 by the turning of the shaft and this gives the snap action which is necessary in the making and breaking of the lamp circuits. Teeth 60 (Figs. 8, 9 and 10) are provided on the commutator 57 and a metal plate 10 61 extends along one side thereof and the edges thereof are bent to cover the faces of three of the teeth, as indicated at 62, leaving the fourth tooth bare, as indicated at 63.

When the parts are in the position shown in Fig. 2, the current passes from one terminal 39 through contact 34 to the metal 62 on one of the teeth, thence through the metal on two other teeth, spring contacts 22 and 27, contacts 20 and 18, 9 and 8, to and through the filaments 5 and 6, 15 thence to the shells 7 and 3, through the bolt 11 and terminal 13 to the other side of the circuit. When the shaft 46 is turned a quarter of a revolution, as shown in Fig. 8, the tooth 60 that has no metal on the face thereof contacts with 20 the spring contact 34, thus opening the circuit through both filaments. The next quarter turn of the shaft 46 brings the commutator 57 into such position, as shown in Fig. 10, that the circuit is closed only through the filament 5, and 25 the next quarter turn brings it into position so that the circuit is closed only through the filament 6, as will be obvious. The positions of the commutator 57 as shown in Figs. 2, 8 and 10 are farther advanced than the normal respective 30 positions, as they are shown in positions near those at which the respective spring contacts snap onto the next teeth.

In the modification shown in Figs. 11, 12 and 13, a switch closing member or commutator 65a 40 rotatably mounted on the shaft 46 is shown. This commutator element 65a comprises a support 65 of insulating material which is made substantially in the form of a square. This support is provided with a curved notch 66 along each 45 edge extending from the respective corners to about the middle of the respective sides of this square. A metal plate 67 is provided on one side of the support 65 and has three bent over portions 68 that lie against three of the curved 50 notches 66. Two V-shaped catches 69 are bent up from the plate 67 so as to have the ends projecting outwardly some distance therefrom.

The catches 69 on the plate 67 are to prevent the lights from flickering when the switch is turned. In order for them to operate for this purpose, holes 100 are provided in the fiber plate 37 (Figs. 3 and 4) in such positions that these catches 69 snap into these holes immediately after the support 65 has been turned each quarter revolution, thus preventing this support from turning backwards when the switch operating shaft is released. If this support were to turn backwards the ends of the spring contacts would be in danger of being sprung away from the bent over portions 68, thus opening the circuit, because of the ends of the notches 66 pushing against the ends of these contacts, but with the catches 69 this will not happen.

In this modified form a ratchet arrangement 70 for the driving of the commutator 65a is provided which consists of a flat metal member 70 having integral prongs 71 which project into corresponding openings in the support 65 to retain this plate in position. A sloping catch 72 is 75 provided on the metal member 70. The switch

operating shaft is provided with a lug which will strike the catch 72 and thus the commutator 65a can be turned by turning the shaft 46 in one direction, but this lug will ride up the sloping slide of the catch 72 and over the catch when the shaft is turned in the opposite direction and the commutator 65a will not be moved.

I claim:

1. In a lamp socket a rotatably mounted shaft; a commutator mounted on said shaft and having portions adapted to engage contacts to effect closing and opening of a circuit including a lamp filament; means to prevent flickering of the light from said filament including an insulating member adjacent said commutator and complementary means on said insulating member and commutator respectively which enter into mutual engagement at predetermined angular movements of said commutator; and means to mount said shaft comprising a base, a slot in said base having 10 opposite side walls, lugs extending from said walls, a clamp engaging said lugs by frictional contact therewith and having a depending skirt portion securing said shaft in said slot.

2. In a lamp socket, a rotatably mounted shaft, 25 a commutator mounted on said shaft and having portions adapted to engage contacts to effect closing and opening of a circuit including a lamp filament, means to prevent flickering of the light from said filament including an insulating member adjacent said commutator and complementary means on said insulating member and commutator respectively which enter into mutual engagement at predetermined angular movements of said commutator, means to mount 30 said shaft comprising a base having a recess therein with opposite side walls, a U-shaped support adapted to be clamped over portions of said base to extend in said recess and having a slot to receive and retain in position said shaft, and 35 means to secure said support to the side wall of said base.

3. In a lamp socket, a base of insulating material having side walls with a recess along one side, a U-shaped support adapted to be placed 45 in said recess and having a slot to receive and retain in position a switch-operating shaft, and means to draw the legs of said U-shaped support together to clamp therebetween the side walls adjacent said recess whereby the support 50 and shaft are held in place.

4. In a lamp socket, a base of insulating material having a recess in its end and along its side, said recess having opposite side walls with lugs projecting therefrom, a U-shaped support 55 adapted to be placed in said recess and over said lugs and having a slot to receive and retain in position a switch-operating shaft, and means on said U-shaped member to clamp said member to said lugs.

5. In a switching mechanism, the combination of an operating shaft, a plurality of spring contact elements, a commutator rotatably mounted on said shaft and adapted to complete circuits between said contact elements, means for 60 driving said commutator by said shaft so as to effect a snap action comprising a spring having one end connected to said shaft and its other end connected to said commutator, whereby the turning of the shaft will build up a torsional tension 65 in said spring which is transmitted to said commutator to turn it on said shaft, and means to prevent unintended movement of said commutator to prevent faulty connection between said commutator and said contact elements comprising 70

ing a member of insulating material adjacent said commutator, said member having recesses therein and said commutator having projections engaging with said recesses at predetermined angular positions of said commutator.

6. In a switching mechanism, the combination of an operating shaft, a plurality of spring contact elements, a commutator rotatably mounted on said shaft and adapted to complete circuits between said contact elements, means for driving said commutator by said shaft so as to effect a snap action comprising a spring having one end connected to said shaft and its other end connected to said commutator, where-
15 by the turning of the shaft will build up a torsional tension in said spring which is transmitted to said commutator to turn it on said shaft, means to prevent unintended movement of said commutator to prevent faulty connection
20 between said commutator and said contact elements comprising a member of insulating material adjacent said commutator, said member having recesses therein and said commutator having projections engaging with said recesses
25 at predetermined angular positions of said commutator, a base of insulating material having a recess therein to receive said contact and said

commutator elements, said base having a slot along one of its sides to receive the operating shaft, and a U-shaped shaft supporting member adapted to be placed over said slot and to engage said base by clamping portions of said base adjacent said slot between the arms of said U-shaped member, said shaft supporting member having a longitudinal slot therein to receive and retain in position the operating shaft.

7. A switching mechanism comprising an operating shaft, a plurality of spring contact elements having their contact surfaces lying in a plane parallel to the axis of said operating shaft, a commutator rotatably mounted on said shaft and adapted to complete circuits between said contact elements, means for driving said commutator by said shaft so as to effect a snap action in making and breaking said circuits, means to prevent unintended movement of the commutator to prevent faulty connection between said commutator and said contact elements comprising an insulating member adjacent said commutator, said insulating member having recesses therein and said commutator having projections thereon to engage with said recesses at predetermined angular positions of said commutator.

JOSEPH WERTZHEISER.
